FIG. 12.

UNITED STATES PATENT OFFICE.

CHARLES H. SCHURR, OF CLEVELAND, OHIO, ASSIGNOR TO THE LEES-BRADNER COMPANY, OF CLEVELAND, OHIO, A CORPORATION OF OHIO.

GRINDING APPARATUS.

Application filed May 15, 1922. Serial No. 561,219.

This invention relates to an apparatus for grinding or surfacing blanks. As illustrating the preferred application of my invention, I have shown it as adapted for grinding or surfacing teeth of gear blanks which teeth have been generated according to the involute rack system.

One object of the invention is to provide an apparatus of this character of relatively few parts capable of co-operation to accurately finish or grind gear teeth.

Another object of the invention is to provide an improved grinding apparatus of relatively simple construction, whereby assembly and replacement of elements for adapting the apparatus to different sized gears or gear blanks may be readily and easily effected.

Another object of the invention is to provide in an apparatus of this character improved means for reciprocating and rolling the gear blank, whereby greater accuracy and uniformity in the finished blank results.

Another object of the invention is to provide an improved mechanism for indexing the gear blank.

Another object of the invention is to provide in an apparatus of this character, means for supporting the free end of the work spindle to prevent wobbling thereof whereby accurate grinding of the gear teeth is insured.

Other objects of the invention will be apparent to those skilled in the art to which my invention relates from the following description taken in connection with the accompanying drawings, in which

Fig. 1 is a front elevation of an apparatus embodying my invention.

Fig. 1^a is a rear elevation of the apparatus (the belt 33 being omitted).

Fig. 2 is a fragmentary transverse section on the line 2—2 of Figs. 1 and 4;

Fig. 3 is a fragmentary section on the line 3—3 of Figs. 1 and 4.

Fig. 4 is a fragmentary section on the line 4—4 of Fig. 3.

Fig. 5 is a section on the line 5—5 of Fig. 4.

Fig. 5^a is an elevation of the parts shown in Fig. 5.

Fig. 6 is a section on the line 6—6 of Fig. 5.

Fig. 6^a is a section on the line 6^a—6^a of Fig. 5.

Fig. 7 is a fragmentary section on the line 3—3 of Fig. 1, being similar to Fig. 3, but showing the indexing mechanism in section

on the line 7—7 of Fig. 9; certain parts of said mechanism being moved to one position of operation.

Fig. 8 is a section on the line 8—8 of Fig. 7.

Fig. 8^a is a detail view of a supporting device.

Fig. 9 is a view of the indexing mechanism, parts being broken away.

Fig. 9^a is a fragmentary view of the indexing mechanism, with parts thereof shown in operated position.

Figs. 9^b and 9^c are perspective views of elements of the indexing mechanism.

Fig. 10 is a fragmentary elevational view of one end of the apparatus showing the reversing mechanism.

Fig. 11 is a section on the line 11—11 of Figs. 10 and 12.

Fig. 12 is a section on the line 12—12 of Fig. 11.

Fig. 13 is a fragmentary sectional view 75 showing the control lever.

Fig. 14 is a fragmentary elevational view of the trimming mechanism.

Fig. 15 is a section on the line 15—15 of Fig. 14.

Fig. 16 is a section on the line 16—16 of Fig. 1.

In the drawings, 1 indicates a main or base frame of suitable construction supporting near one end an upright frame or column 85 2, the latter being fixed to the main frame 1 by any desired means, such as bolts or cap screws 3 (see Fig. 2). The upright frame or column 2 is provided with guides 4 to slidably support a slide 5. 6 indicates a lug or boss, preferably formed integrally with and projecting centrally from the rear side of the slide 5. The boss 6 is formed with an opening through which extends the lower reduced end of a rod 7. The rod 7 is rigidly held in the opening through the boss 6 by a nut 8. The upper portion of the rod is screw-threaded, as shown at 10, and such screw-threaded portion engages a nut 11.

The nut 11 is adapted to be rotated by suitable means 12, whereby the rod 7 may be raised or lowered to vertically adjust the slide 5.

The operating means 12 for the nut 11 may comprise a bevel gear 13 formed integrally with the nut 11 and a beveled pinion 14 meshing with the gear 13. The pinion 14 is fixed to a shaft 15, the outer end of which is fashioned to receive a suitable tool, whereby it

60

- may be rotated in either direction. The bevel wheel 13 is mounted on a thrust bearing 13^a supported on the bottom of a casing 16, which encloses the operating means 12. One side 5 wall of the casing 16 is formed with an opening 17 to form a bearing for the shaft 15. The top wall 16^a of the casing is formed with an opening 18 through which the rod 7 extends when it is moved upwardly. Depending 10 from the top wall 16^a is an annular member 16^b in which the nut 11 rotates, such member serving as a bearing for the nut 11 and acting through it as a guide for the rod 7. 19 indicates a tubular member secured to the top 15 16^a and disposed in alignment with the rod 7 to receive its upper end when the rod is elevated. The casing 16 is preferably provided at its opposite sides with feet 20, which are secured to the column 2 by cap screws 21. 20 The top wall or cover 16^a is removably held in position by cap screws 22.
- 23 indicates a head swiveled in any desired manner on the slide 5, whereby the tool, which in the illustrated embodiment of my invention 25 consists of a relatively large grinding or abrading wheel A, may be positioned at different angles for well-known reasons. The head 23 may be turned by means of a worm wheel 24 secured to the head and engaged 30 by a worm 25 (see Figs. 2 and 4). The worm 25 is fixed to a shaft 26 which is supported in bearings carried in lugs 27 provided on the slide 5; the shaft 26 being held against endwise movement by collars 28 engaging 35 the opposite outer ends of the lugs 27. The shaft 26 is extended at one end and shaped to receive a suitable tool, whereby it may be operated. The head 23 comprises an annular plate 23^a adjustably engaging suitable bearings in the slide 5 and a hollow arm 23^b, which 40 may be formed integrally with the plate 23^a. 29 indicates a tubular member mounted to move endwise within the arm 23^b and adapted to serve as a bearing member for the 45 tool spindle 30. The surfaces of the tubular member 29 and spindle 30 are shaped to provide suitable seats for a plurality of anti-friction bearings 31.
- 32 indicates an element fixed to the shaft 50 or spindle 30 and arranged to rotate it. In the form of rotating means herein disclosed, such element consists of a pulley, fixed to the spindle and preferably arranged between a pair of the anti-friction bearings 31. The 55 tubular member 29 is shaped to provide ample operating space for the pulley 32 and its rear wall as well as the rear wall of the arm 23^b is cut away to permit a driving belt 33 to be carried in and around the pulley 32, as shown 60 in Fig. 2. The belt 33 is guided to the pulley 32 by a pair of pulleys 34, the belt 33 passing from one pulley 34 around a driven pulley 35, fixed to a main driving shaft 36, and thence around a guide pulley 37 to the other pulley 65 34. The pulleys 34, 37, are mounted in suit-

able brackets 34^a, 37^a, respectively, supported by the column 2 in a well-known manner.

The main drive shaft 36 communicates power to other parts or elements of the apparatus in the manner to be later set forth. The shaft 70 36 may be driven in any desired manner, for example by a pulley, driven by a belt 38 running over a driven pulley (not shown).

The tool A preferably comprises an annular disk having a planular face *a* adapted successively to engage the faces of a blank, for example a gear blank B, as the latter is indexed, in the manner to be later described. The tool A is positioned between a pair of inner and outer plates 39, 40, the inner plate 39 having a hub 41 keyed to the spindle 30 and provided at its outer end with an annular seat 39^a for the disk, and the outer plate 40 being clamped against the disk by a nut 42 threaded on the hub 41, and acting against the plate 40 when 85 it is tightened. 43 indicates a nut screw threaded on the outer end of the spindle 30 and engaging the outer end of the hub 41 to secure the latter on the spindle 30. 44 indicates a cap plate having an annular boss 45 90 engaging the outer-most anti-friction bearing 31 and through it and seat 46, next adjacent bearing 31 and seat 47, serving to hold the spindle in position axially.

The bearings 31 on each side of the pulley 95 32 serve principally to take up the lateral load of the pulley and are not provided to take axial thrusts, their outer races fitting loosely enough in the tubular member 29 to move axially therein. This construction allows 100 the expansion and lengthening of the spindle 30 due to heat to take place in opposite directions on each side of the outermost bearings 31. These latter bearings being very near to the planular face of the tool A, no appreciable 105 expansion will occur in that direction and hence the face of the tool will not appreciably move out of its position by expansion of the spindle 30.

The cap plate 44 is secured to the outer end 110 of the tubular member 29 by a plurality of bolts 48 (Fig. 4). 49 indicates a casing or guard for the tool A. The casing 49 comprises a pair of dish-shaped members 49^a, 49^b, having rabbeted inter-engaging circumferential walls secured together by a plurality of screws 50, the inner member being provided with a collar 51 fitted on a reduced portion 52 at the outer end of the arm 23^b and preferably secured to the latter by suitable screws. The casing members 49^a, 49^b, are cut away at their lower portions to permit 115 operative engagement of the tool A with the blank B.

53 indicates as an entirety means for moving the spindle 30 endwise to move the tool A into proper grinding position relative to the blank tooth faces. Of the moving means 53, 53^a indicates a plate secured to the rear end 120 of the tubular member 29, preferably by a 125

plurality of cap screws 53^b, and provided with a rearwardly extending shank 53^c having screw threads 53^d with which a nut 54 engages. The nut 54 comprises two sections, 5 54^a, 54^b, the former being recessed to receive the latter section (see Fig. 4). The nut section 54^b is provided with a flange 54^c, which is secured by suitable cap screws to the nut section 54^a. This arrangement permits the 10 nut sections to be adjusted relative to each other to compensate for wear of the screw threads. The nut 54^a is provided with a worm wheel 54^d, preferably formed integrally therewith. 55 indicates a worm arranged 15 to mesh with the worm wheel 54^d, whereby the nut 54 may be rotated. The worm wheel 54^d engages at its inner side an annular boss provided on an annular rib 54^e provided on the inner wall of the arm 23^b. The wheel 20 54^d is maintained in operative position against the boss by a flanged collar 54^f, the flange of which is secured to the outer edge of the arm 23^b. The worm 55 is fixed to a shaft 55^a mounted in a bearing 55^b, being held on the 25 shaft by a nut 55^{a'} (see Fig. 5). The bearing 55^b fits into an opening 55^c formed in a boss 55^{c'} formed integrally with the wall of the arm 23^b. At its outer end the shaft 55^a carries a hand wheel 56, and a disk 56^a. The 30 hand wheel 56 is loose on the shaft 55^a whereas the disk 56^a is keyed thereto. The circumferential edge of the disk 56^a is provided with a ratchet 56^b with which a dog 56^c, pivoted to the hand wheel 56, engages; the dog 35 56^c being held in engagement with the ratchet 56^b by a spring 56^d. The hand wheel 56 and disk 56^a may be rotated to move the tool spindle 30 endwise, whereby the tool is moved toward and from the blank B to position it for grinding. By providing a detachable connection between the hand wheel and disk, namely the ratchet 56^b and dog 56^c, and correlating with the hand wheel certain instrumentalities, I am enabled to regulate 40 or control the operation of the tool A. For this purpose, I provide the following instrumentalities: 57 indicates an annular groove formed in the web portion of the hand wheel 56, this groove being preferably of T-shape. 45 57^a, 57^b and 57^c indicate a plurality of pins having heads adjustably mounted in the groove 57, being clamped against the walls of the groove by nuts 57^d engaging screw-threaded portions of the pins. The pins 57^a, 55 57^b, 57^c, serve as stops to limit the movement of the hand wheel in either direction, whereas the pin 57^b serves as a gage to regulate or determine the adjustment of the tool for carrying out the grinding operation. 58 indicates a stop device carried by the wall of the arm 23^b. The stop device preferably comprises a rod 58^a having a head member 58^b. The pin 58^a and head 58^b are mounted in a recess or opening formed in a lug 58^c carried by the boss 55^{c'}. The opening in the lug 58^c is enlarged to permit the positioning of a coiled spring around the rod 58^a, such spring acting against a collar 58^d and tending to push the pin 58^a and head 58^b outwardly into position for engagement by the stop pins 57^a and 57^c (see Fig. 6^a); the spring permitting the rod 58^a and head 58^b to be moved endwise beyond or out of the path of movement of the free ends of the stop pins 57^a, 57^c, when it is desired to rotate the hand wheel a greater distance than that permitted thereby. To facilitate the operation of the pin 58^a and head 58^b, the former is provided with a knob 58^e. 70 75 80

In the operation of the elements just described, the stop 57^c is so positioned that it will engage the head 58^b in the revolution of the hand wheel when the tool A is in engagement with the face of one tooth of the blank B. The stop pin or gage device 57^b is 85 then adjusted around the groove 57 relative to the stop pin 57^c a distance corresponding to the depth of cut to be made by the tool A when it is operated.

Assuming that the blank is positioned on the work spindle 64, to be later referred to, the hand wheel 56 is rotated to bring the stop 57^c in engagement with the head 58^b. The slide or carriage 61, to be later described, is then moved laterally so as to move the blank B away from the tool A. The hand wheel is then adjusted or rotated to bring the stop 57^b in alignment with the axis of the head 58^b. The machine is then set in operation and the grinding takes place upon the faces of the teeth of the blank B. Should it be desired to grind additional material from the faces of the blank teeth, the hand wheel may be adjusted to move the stop pin 57^b beyond the stop 58^b and such operations may be 90 repeated until the hand wheel is moved far enough to cause the stop pin 57^a to engage with the head 58^b, which engagement will indicate that the maximum amount of grinding has been effected. To facilitate the positioning of the stop pin 57^b relative to the axis of the head 58^b, the free end of the stop pin 57^b is preferably beveled so that it may ride the head 58^b and the latter is recessed to 95 form a seat for the stop pin 57^b; this construction permitting the stop pin to ride the end of the head 58^b and seat itself in the recess in the end thereof and likewise to be moved out of the recess at will. 264 indicates a set screw extending into the recess for the pin 58^a and so arranged that upon the movement rearwardly of the pin and its rotation in either direction the collar will engage the set screw 264 and maintain the pin 58^a and head 58^b in a retracted position, 100 105 110 115 120 125 130

whereby the hand wheel 56 will be free to rotate. The free end of the shank 58^c is preferably reduced to form a shoulder against which a stop device, such as a washer 59, is clamped by a nut 59^a, the stop device 59 be-

ing arranged to engage the nut 54 and limit the movement of the spindle 30 and tubular member 29 endwise in a direction away from the blank B. 59^b indicates a casing fitted 5 to the outer edge of and supported by the collar 54^c. The casing 59^b encloses the outer end of the shank 53^c and prevents dirt and other material from getting into the arm 23^b. As shown in Fig. 5, the wall of the arm 23^b is 10 shaped to form a housing 59^c for the nut 54 and worms 54^d, 55.

60, 60, indicate a pair of ways or guide-grooves provided on the frame 1 and adapted to receive shoes or guides 60^a, 60^a, on the lower 15 side of the carriage 61, whereby the latter may be reciprocated for reasons which will later appear. The carriage 61 is provided with a pair of spaced pillow blocks 61^a, 61^a, to which are secured cap members 62, 62^a, 20 respectively, forming bearings 63, 63^a, for the work piece or blank carrying spindle 64. The spindle 64 is preferably formed in sections, as follows: a main section 64^a and a detachable section 64^b. The main section 64^a 25 at one end extends through and rotatably fits a sleeve 65, which in turn is rotatably mounted in the bearing 63; at its opposite end the shaft section 64^a is enlarged, as shown at 64^c, such enlarged portion rotatably fitting 30 the bearing 63^a. The enlarged portion 64^c of the shaft is formed with a recess 64^d of tapering shape extending inwardly from its outer end, and such recess 64^d receives the inner tapered end 64^e of the spindle section 64^b. The spindle sections 64^a and 64^b are 35 preferably secured together by the following instrumentalities: 66 indicates an opening extending through the main spindle section 64^a. 66^a indicates a bolt extending through the 40 opening 66, the head of the bolt engaging the outer end of the spindle section 64^a and the inner end of the bolt being screw-threaded into an opening 66^b formed in the inner end of the spindle section 64^b. By tightening the 45 bolt 66^a, the tapered spindle end 64^e will be drawn into the opening 64^d and thus rigidly secure the spindle section 64^b to the section 64^a. The outer end of the spindle section 64^b is preferably reduced to form a shoulder 67, 50 against which the blank B may be clamped in any desired manner, for example, by a nut 67^a. The end of the shaft section 64^b, beyond the threaded portion for the nut 67^a is reduced as shown at 67^b and its end is formed with an 55 opening or recess 67^c arranged axially of the shaft 64^b. By means of the construction just described, it will be seen that that portion of the work carrying spindle to which the blank B is clamped may be detached or removed from the main spindle section and another spindle section provided, whereby different sized blanks may be readily positioned 60 for grinding or finishing by the tool A.

68 indicates means for supporting the outer 65 or free end of the work carrying spindle sec-

tion 64^b, whereby it may be maintained against wobbling to insure relatively accurate grinding or finishing of the sides of the gear teeth. Of the supporting means 68, 69 indicates an arm formed integrally with the carriage 61 and provided with guide-ways 70 in which a slide 71 is adjustably mounted. The slide 71 is provided with a bracket 72, which carries at its free end a seat 73. The seat 73 is shaped to receive a supporting member 73^a, 75 preferably formed with an opening 73^b in which a center 73^c is mounted, these elements being arranged to support the center in axial alignment with the shaft section 64^b with the center projecting into the recess 67^c in the outer end of the shaft section. The supporting member 73^a is secured in the seat 73 by a cap screw 73^d. The inner end of the supporting member has a projecting collar 73^e provided with stepped surfaces, the outer one of which serves as a guide for a cup member 74 and the inner one of which serves as a support for a coiled spring 74^a which tends to push the cup member 74 outwardly against the end of the shaft section 64^b so as to enclose the center and prevent water and grit from getting into the recess 67^c or around the center, the cup member being formed with an opening through which the center 73^c extends. The arm 69 is provided with a longitudinally extending rack 75, with which engages a rack pinion which is carried at the inner end of a shaft 75^a, extending through and mounted in an opening formed in the slide 71. At its outer end, the shaft 75^a carries a wheel 76, whereby the shaft may be rotated, such operation serving to move or adjust the slide 71 in the guideways 70 and thereby move the center 73^c axially of the spindle 64 so that it may be moved into and out of engagement with the spindle section 64^b. The slide 71 may be fixed in any adjusted position by suitable means, such means in the illustrated embodiment of the invention comprising a wedge bar 77 extending through a recess 78 formed in the slide 71 and so disposed that one side of the wedge bar 77 is arranged to engage one of the ways 70 of the arm 69. The wedge bar 77 is formed with one or more openings having threaded walls to receive the threaded ends of rods 79 rotatably mounted in suitable openings formed in the wall of the slide 71. At their upper ends, the rods 79 are formed with handles 79' by means of which they may be rotated, such operation serving to move the wedge into clamping engagement with the adjacent way 70, and the slide against the other way 70.

In the herein disclosed illustrated embodiment of my invention, the gear blank is given a rolling movement such as is required in carrying out the generating principle, on which the blank was cut. For this purpose I preferably employ tapes which are arranged to wind and unwind about a segment con-

nected to the work spindle and having the same diameter as the pitch diameter of the gear blank to be ground and apply power to the spindle first in one direction and then 5 in the other, so that the rotary or oscillatory movement of the latter will be translated by or through the tapes into reciprocatory movement of the carriage 61 in the ways 60, whereby the blank B will be rolled into and out of 10 engagement with the tool A. 80 indicates a driven shaft which operates to oscillate the work spindle 64, whereby the gear blank B is given the rolling motion in the manner just referred to. The shaft 80 is driven first 15 in one direction and then in the opposite direction by a suitable reversing mechanism indicated as an entirety at 81 (which mechanism is shown in detail in Figs. 10, 11 and 12), to which reference will later be made. The 20 outer end of the shaft 80 has bearing in a pair of spaced lugs 83, 83', which are preferably formed integrally with a casing member 84 supported by the adjacent pillow block 61^a and cap member 62 (see Figs. 3 and 7). The 25 casing member 84 co-operates with a casing member 84^a to enclose an indexing mechanism indicated as an entirety at 85. The free end of the shaft 80 is provided with a washer 86 and nut 87, which bear against a thrust 30 bearing 88 supported at the outer end of the lug 83', this bearing taking thrusts of the shaft 80 when it is rotating in one direction. 89 indicates a worm fixed to the shaft 80 and disposed between the lugs 83, 83'. The inner 35 side of the lug 83' is provided with a thrust bearing 90 which takes thrusts when the shaft 80 is rotating in the opposite direction. 91 indicates a worm wheel segment connected by suitable bolts 92 to a disk 93 which 40 is secured by cap screws 94 to the sleeve 65 and forms one element of the indexing mechanism 85, the latter thereby serving as a connection between the sleeve 65 and the work spindle 64, whereby the spindle may be oscillated by the shaft 80. 95 indicates a segment 45 surrounding the spindle 64 or a portion thereof and serving as the wall or surface about which tapes 96, 96^a, wind and unwind. As will be understood, the segment 95 has 50 substantially the same pitch diameter as that of the blank B to be ground and is removably secured to the spindle 64 to permit the substitution of segments having pitch diameters substantially corresponding to any size blank 55 which may be mounted on the spindle. As shown in Fig. 8, the lower portion of the segment 95 is cut away whereby it may be placed on and removed from the spindle 64. At its opposite ends the segment is provided with 60 flanges 97, 97^a; the flange 97 being adapted to be clamped to a flattened lug or shoulder 98 projecting from the inner end of the sleeve 65, and the flange 97^a being adapted to be clamped against a flattened wall on one side 65 of a supporting device 99, which loosely fits the spindle 64; this arrangement permitting (1) the segment 95 to have a fixed relation with the spindle 64 when the spindle is being oscillated as will be later set forth and (2) the spindle 64 to be rotated relative to the 70 sleeve 65 and segment 95 to effect indexing of the gear blank B. 97', 97^a' indicate cross members extending transversely of the spindle 64 and engaging the flanges 97, 97^a, respectively. 100 indicates bolts which extend through openings formed in the opposite ends of the cross members 97', 97^a', and engage cross members 101, 101, provided at the opposite ends of a clamping plate 102, the cross member 101 engaging a lug or shoulder 80 98^a projecting from the sleeve 65 but at the opposite side of its axis from the lug 98, and the cross member 101 engaging a flattened wall at the other side of the supporting device 99, whereby the bolts may operate through the 85 cross members to clamp and removably support the segment 95 in position. The supporting device 99 (see Fig. 8^a) comprises an annular shaped member having at opposite sides flattened walls disposed parallel to each other 90 and spaced a distance equal to the distance between the surfaces of the lugs 98, 98^a, with which the cross members 97' and 101 engage, so that the segment 95 will be arranged parallel to the axis of the spindle 64. The tapes 96, 96^a, extend around the segment 95 and downwardly around the plate 102, their corresponding free ends being carried or folded around rods 103 and clamped against the plate 102 by a bar 104, cap screws 104' being provided to secure the bar 104 against the ends of the tapes. 105 indicates a shoe member disposed substantially tangentially to the segment 95 and extending to either side of the spindle 64 and in a plane parallel to the plane 105 in which the spindle moves. 106, 106^a, indicate a plurality of connecting devices carried by the shoe member 105, (preferably disposed at the opposite ends thereof) for connecting the outer ends of the tapes thereto. In the 110 preferred form of construction I use four tapes, two of which wind around the segment 95 in one direction and are connected to the connecting devices 106 and the remaining two of which wind around the segment 95 in the 115 opposite direction and are connected to the connecting devices 106^a; furthermore, the tapes of each pair alternate with the tapes of the other pair. Each connecting device 106, or 106^a, comprises a lever 106^b pivoted upon a rod or bolt 107 mounted in a standard 108, a pin 109 about which the end of each tape is folded and a clamping plate 110 engaging the folded tape end and clamped thereagainst 120 by a bolt 111 screw-threaded into an opening in the lever 106^b. By pivoting each lever 106^b on the shoe member 105, its outer end may be adjusted to put the tapes connected to it under the proper tension. The adjustment means for each connecting device 106, 106^a, 130

comprises a screw 111^a, fitting and extending through an opening 111^b formed in the wall of the connecting device and engaging at its free end the adjacent end wall of the shoe member 105. By screwing the screw 111^a inwardly, it will cause the device 106 or 106^a to swing outwardly and thus put the tape connected to the latter under the desired tension and adjust its effective length. The upper end of the shoe member 105 is shaped to provide a pair of bars 112 having flanges 113 slidably fitting a pair of guides 114 provided on the lower end of a vertically adjustable support 115. The shoe member is fixedly connected to the support 115 by a plurality of cap screws 116 extending through openings 117 formed in the flanges 115^a of the support 115 and fitting screw-threaded openings in the bars 112. To permit of adjustment of the shoe member 105 relative to the support 115, the openings 117 are elongated (see Fig. 8) so that upon loosening the cap screws 116, the shoe member may be moved to the desired position and then fixed by tightening the screws 116. It will be noted that the bars 112 and the guides 114 extend in a direction at right angles to the axis of the spindle 64; as the connecting devices 106, 106^a are carried by the shoe member 105, it will be seen that the adjustment of the latter along the guides 114 will simultaneously move the connecting devices relative to the spindle 64.

117^a indicates a means for adjusting the shoe member 105 relative to the support 115. Of these means, 118 indicates a boss depending from the support 115, preferably between the bars 112. 119 indicates a screw threaded opening formed in the boss 118, and extending parallel to the bars 112. 120 indicates an opening formed in one end wall of the shoe member 105 in alignment with the opening 119. 121 indicates a rod extending through the openings 119, 120, its inner portion being screw threaded and engaging the threads of the opening 119. The rod 121 is provided with collars 122, 122^a, engaging the opposite faces of the end wall in which the opening 120 is formed and serving to prevent endwise movement of the rod 121 relative to the shoe member 105 when the rod 121 is rotated, so that its rotation in the opening 119 will effect a movement of the shoe member 105 relative to the support 115. The outer end of the rod is preferably shaped to receive a suitable tool.

123 indicates a pair of guides provided on the column 2 and engaging guide walls 124 provided on the support 115, whereby the latter is adjustably connected to and supported by the column 2. The guides 123 and guide walls 124 extend vertically so that the shoe member 105 may be raised or lowered relative to the spindle 64 so as to position it tangentially to any size of segment 95 which may be used in the apparatus. At its upper end the

support 115 is formed with a screw-threaded opening 125, in which a screw threaded rod 126 is adapted to rotate. The rod 126 is supported at its upper end in a bearing 127, being held against endwise movement therein by collars 128, 129. The rod 126 is provided at its upper free end with a crank 130 by means of which it may be turned. The bearing 127 is provided at the outer end of a bracket 128 supported by the adjacent side wall of the column 2.

Of the reversing mechanism 81, I provide a set of change gears, preferably comprising a pinion 131 fixed to the driven shaft 36 (see Fig. 12) and a gear 132 meshing with the pinion 131. The gear 132 is fixed to and continuously drives a counter shaft 133. The shaft 133 is mounted in suitable bearings 134, 135, provided in a housing 136 which is bolted to the main frame as shown in Fig. 1^a. The housing 136 may be provided with an opening 137, adapted to be closed by a cover 138. 139, 140, indicate a pair of gears fixed to the countershaft 133; the former meshing with and transmitting power through an idler 141 loosely mounted on a shaft 142 (see Fig. 11) to a gear 143 loosely mounted on a supplemental shaft 144; and the latter meshing with a gear 145 loosely mounted on the shaft 144. The shaft 144 is preferably mounted in suitable anti-friction bearings 146, 146^a, the former being supported in a suitable seat formed in a collar 147, and the latter being removably mounted in a seat formed in the outer end walls of the housing 136 (see Fig. 12) and held in position by a detachable cap 148. The gears 143, 145, are respectively provided on their opposing sides with collars 149, the free ends of which are shaped to provide clutch elements 150 with either of which a clutch member 151, splined to the shaft 144 is arranged to be engaged. The clutch member 151 is provided with an annular groove 152 in which a yoke or other suitable device 152^a fits, whereby the clutch member 151 may be moved endwise of the shaft 144 into engagement with one of the clutch elements 150 and out of engagement with the other clutch element and into engagement etc., it being understood that (1) when the clutch member 151 engages the clutch element 150 for the gear 145, the shaft 144 will be driven in one direction and (2) when the clutch member 151 engages the clutch element 150 for the gear 143 the shaft 144 will be driven in the opposite direction—such reversed direction being effected by interposing the idler 141 between the gears 139 and 143. The yoke member 152^a is provided with studs 152^b (one being shown in Fig. 10) which are engaged by a lever 152^c, mounted on a stud shaft 152^d. 153 indicates a gear fixed to the shaft 144 and meshing with a gear 153^a loosely mounted on the shaft 80^b, the outer end of which is mounted in suitable bearings provided in

the housing 136. For reasons which will later appear, the gears 153, 153^a are preferably spiral gears, and the gear 153 is relatively wide so that it may move longitudinally of the shaft 144 without being disconnected from the gear 153^a. 154 indicates a clutch interposed between the gear 153^a and the shaft 80^b and controlled manually by a handle or lever 155. The clutch 154 comprises a clutch element 154^a fixed to the gear 153^a and a sleeve 154^b splined to the shaft 80^b and having a clutch element 154^c engageable with the clutch element 154^a. The sleeve 154^b is operated endwise of the shaft 80^b by a yoke member 155', slidably mounted on a rod 156, and the yoke member 155' is operated by a lever 157 fixed to a rock shaft 158 mounted in a cover 159 (see Fig. 13) bolted in any suitable manner, as indicated at 160, to the housing 136. The rock shaft 158 is operated by the handle or lever 155. 161 indicates a worm preferably integrally formed with a sleeve 161^a fitting on and fixed in any desired manner to the shaft 80^b. The worm 161 meshes with a worm wheel 162 fixed to a transverse shaft 163 mounted in suitable bearings 164, as shown in Fig. 11. At its outer end, the shaft 163 carries a disk 165 on which are mounted a pair of spaced stops 166, 167. 168 indicates a lever pivoted at 169 to a boss 170. One end of the lever 168 extends upwardly between the stops 166, 167, so as to be engaged thereby. The opposite end of the lever 168 is pivotally connected to a link 171 which in turn is pivotally connected to the lever 152^c at 263. The shaft 80 is preferably formed in sections, one being indicated at 80^a, and the other indicated at 80^b. The section 80^b comprises a sleeve portion 80^c into which the adjacent end of the section 80^a fits. The remaining portion of the shaft section 80^b is reduced to receive the worm sleeve 161^a, gear 153^a and clutch sleeve 154^b, such arrangement permitting the provision of thrust bearings 172 between the shaft 80 and the walls of the bearings therefor (see Fig. 12).

The operation of the reversing mechanism may be briefly described as follows: The power of the shaft 36 is transmitted through the change gears 131 and 132, shaft 133 and one of the gears 143, 145, to the shaft 144, accordingly as the clutch member 151 is engaged with the one or the other thereof. The shaft 144 through the gears 153, 153^a, and clutch 154 will rotate the shaft 80 and the latter in turn, through the worm 161 and worm wheel 162, will rotate the transverse shaft 163. The latter shaft rotates the disk 165 and causes one of the stops, for example stop 166, to engage the lever 168 and move it about its pivot, such operation serving to disengage the clutch member 151 from one gear clutch element 150 and engage it with the clutch element 150 of the other gear. The

shafts 144, 80 and 163 will then rotate in the opposite direction until the stop 167 engages the lever 168 and swings it to its first position. Such reversing will continue as long as the machine operates or until the clutch 154 is thrown out by movement of the lever 155.

172' indicates as an entirety means for operating the lever 168 with a relatively quick movement to throw the clutch member 151 into engagement with either of the clutch elements following its disengagement from either one thereof. Of these means, 173 indicates a lug carried by the lever 168. 174 indicates an arm pivoted at 175 and carrying a pair of cams 176 shaped to form a shoulder over which the lug rides from one cam 176 to the other. 177 indicates a spring connected to the arm 174 and to an eye bolt 178 and tending to swing the arm 177 upwardly about its pivot. When the clutch member is in one position, that is, in engagement with one of the clutch elements 151, the lug 173 is disposed in engagement with one of the cams. When one of the stops engages the lever 168 and moves it toward its other position, the lug 173 in riding the adjacent cam 176 will cause the arm 177 to swing downwardly and put the spring 177 under tension. When the lug 173 passes over the shoulder formed by the cams, the spring acting through the other cam 176 and the lug 173 will cause the lever 168 to swing with a relatively quick movement over to its other position. When the reversing mechanism operates to reverse the rotation of the shaft 80, these elements operate in the same manner in the opposite direction. By forming the link 171 with an elongated slot to receive the pivot provided between it and the lever 168, the latter, when operated in either direction by the action of the adjacent cam, will attain considerable momentum before the pivot engages the end wall of the slot in the link 171, so that the latter will be quickly and positively operated. The lug 173 is preferably provided with a roller 173' whereby it may ride the cams with minimum friction.

It will be noted from the foregoing description that the shaft 80 is rotated for a predetermined number of revolutions in either direction. By adjusting either stop 166, 167, the shaft 80 may be rotated in either direction a larger or smaller number of times. For this purpose, each of the stops 166, 167, comprises a pin 179, having a head slidably fitting an annular T-groove 180 formed in the disk 165, the pin having a threaded portion to receive a nut 181, whereby the head may be clamped against the walls 125 of the groove 180.

182 indicates a pair of collars fixed to the shaft 144 and disposed upon opposite sides of the gear 153. 183 indicates a spring coiled around the shaft 144 at either side of the gear 130

153 and disposed between it and the adjacent collar 182. As clearly shown in Fig. 12, the gear 153 is splined to the shaft 144 but is free to move longitudinally thereof in either 5 direction against the tension of one of the springs 183. As already described, the gears 153, 153^a, are spiral gears so that their resulting meshing action causes a thrust in one direction or the other accordingly as shaft 10 144 is transmitting power. Accordingly, when the rotation of the shaft 80 is reversed and it, through the tapes 96, 96^a, starts to move the carriage 61 in the corresponding opposite direction, the reaction of the spiral 15 teeth of the gears 153, 153^a, incident to picking up the carriage in transmitting power through the spiral teeth of the gears 153, 153^a, will cause the gear 153 to slide endwise of the shaft 144 against one of the springs 183 20 which will thereupon absorb or cushion such thrust movement; the effect of which will be to start the movement of the carriage in the reversed direction relatively slowly without jerking it. The springs 183 are preferably 25 of a size to return the gear 153 to substantially its mid-position after the carriage 61 has been reversed and started on its return movement.

Of the indexing mechanism 85, 184 indicates a block secured in any desired manner, for example, by dowel pins 185 and a cap screw 186 to the disk 93. The block 184 is provided with a pair of guide walls 184^a, preferably extending parallel to a line that is radial 30 of the axis of the work spindle 64 and arranged to slidably support a plunger 187. The face of the plunger 187 is engaged by a pair of plates 187^a, whereby it is held in the guides 184^a. 188 indicates a dog carried at 35 the lower or inner end of the plunger 187 and arranged successively to project into slots or recesses 189 formed in the circumferential edge of a plate 190 fixed, preferably through a hub member 260, to the outer end of the 40 work spindle 64, by a nut 261. The slots or recesses 189 are uniformly spaced around the plate 190 and correspond in number to the number of teeth of the blank B to be ground. When the dog 188 is in one of the slots 189 the 45 disk 93 and plate 190 are connected together so that the power of the shaft 80 is transmitted therethrough to rotate the spindle 64 and to translate such rotary movement into rectilinear movement of the slide or carriage 61, whereby the generating movement of the gear blank B may be effected during engagement of the tool A therewith, as already described. Such engagement takes place during the 50 movement of the disk 93, plunger 187, plate 190 and spindle 64 in an anticlockwise direction (as viewed in Fig. 9) to their extreme position and back to their starting position. As these elements near the end of their movement in the clockwise direction, the blank B 55 moves out of engagement with the tool A and

indexing of the blank takes place, that is, the dog 188 disengages the adjacent slot 189, and the plate 190 is locked against rotation so that the dog can move around the plate 190 and engage the next or succeeding slot 189 to 70 connect itself with the plate to move it in the anticlockwise and then back again, such operations being repeated until all of the teeth of the gear blank B have been ground. 191 indicates a roller mounted on a shaft 192 extending through openings formed in the wall of the dog 188 and the plunger 187 and held in position by a nut 193, said shaft co-operating with a screw 194 to rigidly secure the dog to the plunger. 195 indicates a rack provided at or along one side of the plunger 187 and arranged to be engaged by a segment of a rack pinion 196 (see Fig. 9^c). The segment 196 is carried by a collar 196^a rotatably mounted on a stud shaft 197 mounted on the disk 93. 80 The collar 196^a is provided with a tail-piece 197^a which engages a trip 198 pivotally mounted in a block 199 fitting in an opening formed in the casing member 84^a. The trip 198 is maintained against a stop 200 by a 90 spring 201. In the movement of the disk 93 and other elements above referred to in the clockwise direction, as viewed in Fig. 9, the tail-piece is engaged by the trip 198, such engagement causing the rotation of the collar 95 196^a as the tail-piece rides the trip; the collar in turn moves the rack pinion segment 196 and it operates the plunger 187 and disengages the dog 188 from the adjacent slot 189 in the plate 190. 202 indicates an arc shaped 100 guide arranged to receive the roller 191 as the elements move clockwise. The guide 202 is positioned to receive the roller 191 prior to the radial movement of the plunger by the collar 196^a. The guide 202 is secured to a support 203 the opposite ends of which are slidably mounted in a pair of guides 204, 204, disposed in a radial line and carried by integral walls of the casing member 84^a. As the roller 191 enters the guide 202 prior to the outward 110 movement of the plunger 187, it will be seen that when the latter is operated, the roller 191 will operate through the guide 202 to move the support 203 radially outwardly, against the tension of one or more springs 204 connected thereto and to fixed devices 205 provided on the casing member 84^a (see Fig. 9). 206 indicates a pawl pivoted on a shaft 206 carried by a bearing block 207. The block 207 is mounted in an elongated opening formed 120 in the support 203, being maintained in position against movement endwise of the slot by a pair of screws 208, which engage the opposite ends of the block. The arrangement permits the block to be adjusted in a direction tangentially to a circle concentric to the axis of the spindle 64, so that the free end of the pawl 206 can be moved to different positions whereby it may be caused to operate in correlation with the movement of the dog 188. 130

The pawl 206 is positioned to project into one of the slots 189 after the dog has been removed therefrom.

The function of the pawl is to engage the plate 190 and lock it against movement following the disengagement of the dog 188 therefrom. The pawl is preferably arranged to enter the slot 189 from which the dog 188 has moved, the plate 190 being flanged as shown at 190^a so that the walls of the slots 189 will be in the path of movement of the pawl 206. The pawl 206 is provided with a tail 209 to which one of the springs 204' is connected, thus permitting the pawl 206 to 15 yieldingly engage the inner wall of the flange 190^a, when the support 203 is moved outwardly, ready to enter a slot 189 as it moves clockwise.

As already set forth, the trip 198 actuates the collar 196^a which in turn disengages the dog from the plate 190, as these parts move clockwise. As soon as the tail-piece 197^a passes the trip 198, the plunger 187 and the dog 188 are free to move inwardly radially, 20 being acted upon by the springs 204' acting through the support 203 and guide 202. However, these elements are maintained approximately in their outward position by the circumferential edge of the plate 190 with

30 which the dog 188 engages after the tail-piece 197^a passes the trip 198. As the disk 93 and plunger 187 continue to move clockwise, the dog 188 will ride on the circumferential edge of the plate 190 until it reaches 35 the next slot 189 into which it will project and permit the springs 204' to move the support 203 and elements carried by it inwardly to their locking position, thus causing the pawl 206 to disengage the adjacent slot 189. 40 This operation again secures the disk 93 and plate 190 together, thereby completing the indexing of the blank B. The direction of rotation of the shaft 80 is reversed following the latter operation, so that the next 45 grinding operation can be effected.

The trip 198 is pivoted so that it may swing in one direction and permit the tail-piece 197^a to pass it when the elements are moving counter-clockwise. To prevent disengagement of the dog 188 from each of the 50 slots 189 throughout that portion of the movement of the elements during the grinding operation I provide the following instrumentalities:

55 209 indicates an arc shaped member carried by the casing member 84^a and extending throughout the path of movement of the plunger during that portion of its movement in which the grinding operations take place. 60 The plate 209 is secured to the casing member 84^a by a plurality of cap screws 210. 211 indicates a lever pivotally mounted upon the stud shaft 197 and carrying at its outer end a pin 212 on which a roller 213 is loosely 65 mounted, the latter serving to roll on the plate

209. The collar 196^a is provided with an arm 214 which is disposed between a pair of abutments 215 provided on the tail-piece 216 of the lever 211. The arm 214 is yieldingly maintained against one of the abutments by 70 a flat spring 214^a. As will be understood from Fig. 9, the wall 209 will prevent movement of the lever 211 about the shaft 197 and the lever 211, through the engagement of its tail-piece 216 with the arm 214, will prevent 75 rotation of the collar 196^a in a counter-clockwise direction (as viewed in Fig. 9), so that the plunger 187 will be locked against movement upwardly in a radial direction. As a result of this construction, the dog 188 will 80 be maintained in the adjacent slot 189 during the grinding operations. As shown in Fig. 9, the arc shaped wall 209 terminates at a point ahead of the position occupied by the plunger 187 when it is moved upwardly by 85 reason of the engagement of the tail-piece 197^a with the trip 198, thus permitting movement of the plunger following the disengagement of the blank B from the tool A.

The casing members 84, 84^a, are preferably 90 connected together by devices, indicated as an entirety at 216^a, whereby the position of the trip 198 may be adjusted to effect operation of the plunger 187 at any desired point 95 throughout the travel of the disk 93. For this purpose the flanges of the casing members 84, 84^a, are formed with openings 216^b, to receive clamping elements, such as suitable screws 216^c, the openings 216^b in the casing member 84^a being elongated as shown in Fig. 100 9, so that it may be moved about the axis of the spindle 64 and then clamped to the casing member 84.

217 indicates as an entirety means for preventing the rotation of the tubular member 29 and for locking it in any of the positions to which it may be moved by the hand wheel 56. Of these means 218, 218^a, indicate a pair 105 of longitudinal grooves formed in the tubular member 29 and extending parallel to 110 each other. 219 indicates a pin extending through an opening 220 formed in the frame or arm 23^b, the free end of the pin 219 engaging one wall of the groove 218 and serving as an abutment to prevent rotation of the tubular member 29 in one direction, but permitting it 115 to move longitudinally of its axis. The pin 219 is preferably provided with a head 221 which is secured to thickened walls of the arm 23^b by a plurality of cap screws 222. 120 223 indicates a plunger slidably fitting an opening 224 formed in the arm 23^b in alignment with the opening 220 and engaging one wall of the groove 218^a. The plunger is connected at its outer end to a rod 225 which has 125 screw-threaded engagement with a plate 226 secured by cap screws 227 to thickened walls of the arm 23^b. Rotation of the rod 225 will move it endwise inwardly or outwardly according to the direction of its rotation; when 130

moved inwardly the rod will move the plunger 223 inwardly against the wall of the groove 218^a and hence clamp the tubular member 29 against movement. When the plunger 223 is moved outwardly it will release the tubular member. As will be evident from Fig. 16, the free end of the plunger 223 cooperates with the pin 219 to prevent rotation of the tubular member 29 about its axis and 10 also to guide it axially.

228 indicates as an entirety a trimming mechanism for trimming the planular face *a* of the tool A. Of the trimming mechanism, 228^a indicates a diamond projecting from the 15 outer end of a sleeve 229, the diamond being supported in the sleeve in a well-known manner and positioned against the inner end of a plunger 230 which has screw-threaded connection with the inner wall of the sleeve 229 20 whereby it may be moved endwise. The sleeve 229 is mounted in an opening 231 formed in an arm 232 which is formed integrally with and extends laterally from a shaft 233. The shaft 233 is rotatably mounted 25 in a bearing 234 provided on a standard 234' secured by a plurality of bolts 235 to the wall of the arm 23^b. The sleeve 229 is secured in the opening 231 by a suitable cotter pin 235'. The shaft 233 has a reduced portion 236 and surrounding such reduced portion is a sleeve 237 30 provided at one end with a worm wheel 238 with which a worm 239 meshes. The worm 239 is connected to a shaft 240 mounted in an opening formed in the standard 234'. The 35 shaft 240 is provided with a crank 241, whereby it may be operated to rotate the shaft 233 and swing the arm 232 from an inoperative position beyond the periphery of the tool A to an operative position, in engagement with 40 the planular face of the tool A, the casing member 49^b being formed with an opening 242 to permit the positioning of the diamond 228^a as shown. The diamond itself may first be positioned relatively to the casing by adjusting the sleeve 229 axially in the arm 232 until, as shown in Fig. 1, the diamond touches one wall of the opening 242 in the casing member 49^b. Then when the arm 232 has been 45 swung to bring the diamond in front of the tool face, the tool A may be adjusted axially in the manner described hereinbefore to locate it relatively to the diamond (and therefore relatively to the wall of the casing); or to enable the diamond to cut and dress the tool A 50 to a true surface in proper relation to the wall of the casing. Since the position of the casing is fixed relatively to the work carrying spindle 64 and gear B, by thus positioning the diamond relatively to the casing and 55 then locating the face of the tool relatively to the diamond the face of the tool can at any time be accurately located relatively to the work piece or gear B.

The wall of the casing is used as the reference point or reference station relatively

to which the diamond is adjusted, because of its convenient location. But obviously any suitable point or station that is fixed relatively to the frame of the machine or to the gear may be used.

70 The outer end of the shaft 233 is preferably provided with screw threads to take a nut which engages a coiled spring 243 engaging the sleeve 237 and through it serving to yieldingly maintain the shaft 233 in the bearing 234 with the shoulder 244 at its inner end in engagement with the adjacent end of the bearing.

75 245 indicates a hand wheel having a hub 246 loosely fitting the outer end of the shaft 80 (see Fig. 12), being held thereon by any suitable means, for example, by a washer 247 and a nut 248. The inner end of the wheel hub 246 rotatably fits the outer end of a bushing 249 which forms one bearing for the shaft 80. 80 The end wall of the hub 246 is provided with clutch elements 250 adapted to be engaged by the clutch elements 251 on the adjacent end of the clutch member 154, so that when the latter is disengaged from the gear 153^a, it will 85 connect the shaft 80 to the hand wheel 245. This construction permits the shaft 80 to be manually rotated to adjust the carriage or slide 61 or the gear blank B relative to the 90 tool A.

95 252 indicates a shaft extending from the front side of the frame 1 to the rear side thereof. At its rear end the shaft 252 is provided with a rack pinion 253 which engages a rack 254. The rack 254 is connected to a belt shifter 255 and operates the belt 38 from the loose pulley 256 to the fast pulley 257 in a well-known manner. At its front end the shaft 252 is provided with a crank 258, whereby it 100 may be readily operated.

105 It will be understood that many alterations and widely differing embodiments of the invention will suggest themselves to those skilled in the art to which my invention relates without departing from the spirit and scope thereof. The disclosures and description herein are purely illustrative and are not intended to be in any sense limiting.

110 What I claim is:

115 1. In apparatus of the class described, the combination with a tool and a carriage on which a blank is mounted for engagement by the tool, of means for reciprocating said carriage, said means including a driven shaft, a countershaft having connections with said driven shaft, a supplemental shaft, alternative connections between said counter and supplemental shafts having a clutch member arranged to engage either of said connections, 120 whereby said supplemental shaft may be driven in either direction, a separate shaft having operative connection with said carriage, means operated by said separate shaft for shifting said clutch member, and means between said supplemental and separate shafts 125 130

for driving the latter and cushioning the carriage in the reversal of movement thereof.

2. In apparatus of the class described, the combination with a tool and a carriage on which a blank is mounted for engagement by the tool, of means for reciprocating said carriage, said means including a supplemental shaft, a countershaft means for driving said supplemental shaft alternately in opposite directions, a shaft having operative connection with said carriage, means operated by said last mentioned shaft for shifting the elements of said driving means which controls the direction of rotation of said supplemental shaft, and means between said supplemental shaft and the last mentioned shaft for driving the latter and cushioning the carriage in effecting reversal of movement thereof.

3. In apparatus of the class described, the combination with a tool and a carriage on which a blank is mounted for engagement by the tool, a supplemental shaft, means for driving said shaft alternately in opposite directions, a shaft having operative connection with said carriage, means operated by said last mentioned shaft for shifting the element of said driving means which controls the direction of rotation of said supplemental shaft, a gear train between said supplemental shaft and the last mentioned shaft for driving the latter, two of the gears of said gear train being helical gears and one movable relative to the other on its axis, and springs engaging said movable helical gear and arranged to take the thrust thereon incident to the inertia of the carriage in effecting the reversal of movement thereof.

4. In apparatus of the class described, the combination with a tool and a carriage on which a blank is mounted for engagement by the tool, a supplemental shaft, means for driving said shaft alternately in opposite directions, a shaft having operative connection with said carriage, means operated by said last mentioned shaft for shifting the element of said driving means which controls the direction of rotation of said supplemental shaft, helical gears on said shafts for transmitting the power of the supplemental shaft to the other shaft, one of the said gears being slideable on its shaft, and springs engaging said slideable gear arranged to take the end thrusts thereof incident to the inertia of the carriage in effecting the reversal of movement thereof.

5. In apparatus of the class described, the combination with a tool and a carriage on which a blank is mounted for engagement by the tool, of means for reciprocating said carriage, said means including a driven shaft, a countershaft having change gear connections with said driven shaft, a supplemental shaft, alternative connections between said counter and supplemental shafts having a clutch member arranged to engage either of said connections, whereby said supplemental

shaft may be driven in either direction, a separate shaft having operative connection with said carriage, means operated by said separate shaft for shifting said clutch member, and means between said supplemental and separate shafts for driving the latter and cushioning the carriage in the reversal of movement thereof.

6. In apparatus of the class described, the combination with a carriage adapted to be reversed of reversing means therefor including a supplemental shaft, means for driving said shaft alternately in opposite directions, means operatively connecting the supplemental shaft and the carriage to reciprocatively move the carriage, the said means including two power transmitting elements one having an inclined surface upon which it is engaged by the other, the two elements being thereby adapted to move relatively when transmitting energy, and a resilient element opposing said relative movement and arranged to accumulate a part of the energy delivered by the supplemental shaft to stop and reverse the carriage.

7. In apparatus of the class described, the combination with a movable carriage of means for reversing its direction of motion, including a movable element adapted to transmit reciprocatory movement to the carriage alternately in opposite directions through two power transmitting elements one having an inclined surface upon which it is engaged by the other, the two elements being thereby adapted to move relatively when transmitting energy, and a resilient element opposing said relative movement and arranged to accumulate a part of the energy delivered by the movable element to stop and reverse the carriage.

8. In a machine, a cushioned power transmitting device including a rotating power supplying element, a rotating power receiving element, a train of gears connecting the two elements two of which are helical gears and thereby adapted to move relatively, axially, when transmitting power, and a resilient element opposing said relative movement and arranged to accumulate a part of the energy delivered by the power supplying element when above a pre-determined amount.

9. In apparatus of the class described, the combination of a frame, a carriage mounted to reciprocate thereon, a pair of supports on said carriage, a work-carrying spindle rotatably mounted in said supports, a sleeve interposed between said spindle and one of said supports, a segment disposed between said supports in parallel relationship to the axis of said spindle and engaging said sleeve at one end, means for supporting the other end of said segment, and flexible members connected to said frame and arranged to wind on and unwind from said segment.

10. In apparatus of the class described, the combination of a frame, a carriage mounted to reciprocate thereon, a pair of supports on said carriage, a work-carrying spindle rotatably mounted in said supports, a sleeve interposed between said spindle and one of said supports, a segment disposed between said supports, means for connecting one end of said segment to said sleeve, and a device 10 rotatably fitting said spindle to which the other end of said segment is connected.

11. In apparatus of the class described, the combination of a frame, a carriage mounted to reciprocate thereon, a pair of supports 15 on said carriage, a work-carrying spindle rotatably mounted in said supports, a sleeve interposed between said spindle and one of said supports, a segment disposed between said supports, means for connecting one end of 20 said segment to said sleeve, and a device rotatably fitting said spindle to which the other end of said segment is connected, and means for connecting said sleeve and spindle together, and means operating through said 25 connections for oscillating said spindle.

12. In apparatus of the class described, the combination of a frame, a carriage mounted to reciprocate thereon, a tool carried by said frame, a work-carrying spindle on said carriage, means for oscillating said spindle and reciprocating said carriage, means carried by said carriage and engaging said spindle beyond the blank carried thereby for steady- 30 ing the outer end of said spindle.

13. In apparatus of the class described, the combination of a frame, a carriage mounted to reciprocate thereon, a tool carried by said frame, a work-carrying spindle on said carriage, means for oscillating said spindle and reciprocating said carriage, adjustable means 40 carried by said carriage and engaging said spindle beyond the work carried thereby for steady- 45 ing the outer end of said spindle.

14. In apparatus of the class described, the combination of a frame, a carriage mounted to reciprocate thereon, a tool carried by said frame, a work-carrying spindle on said carriage, means for oscillating said spindle and reciprocating said carriage, a center arranged 50 to engage said spindle beyond the work carried thereby, a support adjustably carried by the said carriage for supporting said center, and means enclosing said center and engaging the free end of the spindle for preventing 55 foreign substances from contacting with said center and shaft end.

15. In apparatus of the class described, the combination of a frame, a tool on the frame, a carriage mounted to reciprocate on said 60 frame, a work-carrying spindle rotatably mounted on said carriage, a segment in fixed relation to said spindle during the operation of said tool, a shoe member, a plurality of tapes connected to said shoe member at op-

posite sides of said spindle and arranged to wind on and unwind from said segment, power means connected to said spindle for oscillating it, and means for adjustably supporting said shoe member on said frame, whereby it may be moved in a plane parallel 70 to the movement of said carriage.

16. In apparatus of the class described, the combination of a frame, a tool on the frame, a carriage mounted to reciprocate on said frame, a work-carrying spindle rotatably mounted on said carriage, a segment in fixed 75 relation to said spindle during the operation of said tool, a shoe member, a plurality of tapes connected to said shoe member at opposite sides of said spindle and arranged to wind on and unwind from said segment, power means connected to said spindle for oscillating it, and means for adjustably supporting said shoe member on said frame, whereby it may be moved in a plane parallel 80 to the movement of said carriage, the supporting means for said shoe member being adjustable vertically.

17. In apparatus of the class described, the combination of a frame, a carriage mounted to reciprocate on the frame, a segment mounted to oscillate on the carriage, a shoe member, a plurality of tapes connected to said shoe member at opposite sides of said segment and arranged to wind on and unwind therefrom, power means to oscillate said segment, and means for adjustably supporting said shoe member on said frame whereby it may be moved relatively to the axis of said 95 segment.

18. In apparatus of the class described, the combination of a frame, a tool on the frame, a carriage mounted to reciprocate on said frame, a work-carrying spindle rotatably mounted on said carriage, a segment in fixed 105 relation to said spindle during the operation of said tool, a shoe member, a plurality of tapes connected to said shoe member at opposite sides of said spindle and arranged to wind on and unwind from said segment, power means connected to said spindle for oscillating it, means for adjustably supporting said shoe member on said frame, whereby it may be moved in a plane parallel to the movement of said carriage, and means for indexing said spindle.

19. In apparatus of the class described, the combination with a frame, of a slide mounted thereon, a work-carrying spindle on the slide, a tool, a tool spindle, means for operating said work carrying spindle and slide to impart to the work carried by said spindle a generating motion relative to the said tool, a support for said tool spindle comprising a hollow arm, a tubular member, within which said tool spindle is supported, slidably fitting said hollow arm, driving means connected to the spindle intermediate the ends of said 115 120 125

member, and means for sliding said tubular member endwise of said arm to move the tool relative to the blank.

20. In apparatus of the class described, the combination with a frame, of a slide thereon, a work carrying spindle, a tool, a tool spindle, means for operating said work carrying spindle and slide to impart to the work carried by the spindle a generating motion relative to the said tool, a support for the tool spindle comprising a hollow arm, a tubular member within which said tool spindle is supported, slidably fitting said hollow arm, means for sliding said tubular member endwise of said arm to adjust the tool relative to the work, and means to prevent rotation of said tubular member.

21. In apparatus of the class described, the combination with a frame, of a slide thereon, a work carrying spindle, a tool, a tool spindle, means for operating said work carrying spindle and slide to impart to the work carried by the spindle a generating motion relative to the said tool, a support for the tool spindle comprising a hollow arm, a tubular member, within which said tool spindle is supported, slidably fitting said hollow arm, means for sliding said tubular member endwise of said arm to adjust the tool relative to the work, means to prevent rotation of said tubular member, and means for clamping said tubular member in its adjusted position.

22. In apparatus of the class described, the combination with a frame, of a slide mounted thereon, a work carrying spindle, a tool, a tool spindle, means for operating said work carrying spindle and slide to impart to the work carried by said spindle a generating motion relative to said tool, a support for said tool spindle comprising a hollow arm, a tubular member, within which said tool spindle is supported, slidably fitting said hollow arm, and means for sliding said tubular member endwise of said arm to adjust the tool relative to the work, said sliding means comprising a screw-threaded shank, a nut engaging with said shank and means for operating said nut.

23. In apparatus of the class described, the combination with a frame, of a slide mounted thereon, a work carrying spindle on the slide, a tool, a tool spindle, means for operating said work carrying spindle and slide to impart to the work carried by said spindle a generating motion relative to said tool, a support for said tool spindle comprising a hollow arm, a tubular member, within which said tool spindle is supported, slidably fitting said hollow arm, and means for sliding said tubular member endwise of said arm to adjust the tool relative to the work, said sliding means comprising a screw-threaded shank, a sectional nut engaging with said shank and means for operating said nut.

24. In apparatus of the class described, the

combination with a frame, of a slide mounted thereon, a work carrying spindle on the slide, a tool, a tool spindle, means for operating said work carrying spindle and slide to impart to the work carried by said spindle a generating motion relative to said tool, a support for said tool spindle comprising a hollow arm, a tubular member, within which said tool spindle is supported, slidably fitting said hollow arm, means for sliding said tubular member endwise of said arm to adjust the tool relative to the work, said sliding means comprising a screw-threaded shank, a nut engaging with said shank and means for operating said nut, and means carried by said shank and engaging said nut to limit the movement of said tubular member in one direction.

25. In apparatus of the class described, the combination with a frame, of a slide mounted thereon, a work carrying spindle on the slide, a planular faced tool, a tool spindle, means for operating said work carrying spindle and slide to impart to the work carried by said spindle a generating motion relative to said tool, and means for moving said tool spindle endwise to adjust the tool relative to the work, said moving means including a pair of relatively movable members adjustably connected together and devices for controlling the movements of said members.

26. In apparatus of the class described, the combination of a frame, a slide mounted thereon, a work piece carrying spindle on the slide, a planular faced tool, a tool spindle, means for operating said work piece carrying spindle and slide, and means for moving said tool spindle endwise to adjust the tool relatively to the work piece, said moving means including a pair of relatively movable members adjustably connected together, and adjustable devices for controlling the movement of said members.

27. In apparatus of the class described, the combination with a frame of a slide mounted thereon, a work piece carrying spindle on the slide, a planular faced tool, a tool spindle, means for operating said work piece carrying spindle and slide, means for moving said tool spindle endwise to position the tool relatively to the work piece, and means for restricting said movement to a predetermined amount.

28. In apparatus of the class described, the combination with a frame, of a slide mounted thereon, a work carrying spindle on the slide, a planular faced tool, a spindle for said tool, means for operating said work carrying spindle and slide to impart to the work carried by said spindle a generating motion relative to said tool, and means for moving said tool spindle endwise to adjust the tool relative to the work, said moving means including a pair of relatively movable members adjustably connected together and devices inter-

posed between one of said members and said frame for controlling the movements of said members.

29. In apparatus of the class described, the combination with a frame, of a slide mounted thereon, a work carrying spindle on the slide, a planular faced tool, a spindle for said tool, means for operating said work carrying spindle and slide to impart to the work carried by said spindle a generating motion relative to said tool, and means for moving said tool spindle endwise to adjust the tool relative to the work, said moving means including a pair of relatively movable members adjustably connected together and adjustable devices interposed between one of said members and said frame for controlling the movements of said members.

30. In apparatus of the class described, the combination of a frame, a carriage mounted thereon, a work carrying spindle on said carriage, a planular faced tool, a spindle for said tool, means for operating said work carrying spindle and carriage, and means for moving the tool spindle endwise to adjust the tool relative to the work, said means including a pair of relatively movable members adjustably connected together, a stop carried by said frame and a plurality of stops carried by one of said members and operatively engaging the stop carried by the frame.

31. In apparatus of the class described, the combination of a frame, a carriage mounted thereon, a work carrying spindle on said carriage, a planular faced tool, a spindle for said tool, means for operating said work carrying spindle and carriage, and means for moving the tool spindle endwise to adjust the tool relative to the work, said means including a pair of relatively movable members adjustably connected together, a stop carried by said frame and a plurality of stops carried by one of said members and operatively engaging the stop carried by the frame, the latter stop being yieldingly maintained in its operative position.

32. In apparatus of the class described, the combination of a frame, a carriage mounted thereon, a work carrying spindle on said carriage, a planular faced tool, a spindle for said tool, means for operating said work carrying spindle and carriage, operable means for moving the tool spindle endwise to adjust the tool relative to the work, a stop carried by said frame and a stop associated with said operable means and operatively engaging the stop carried by the frame.

33. In apparatus of the class described, the combination of a frame, a carriage mounted to reciprocate on said frame, a work carrying spindle on said carriage, means for operating said carriage and spindle to impart to the work carried by the latter a generating motion relative to a tool, a slide adjustably mounted on said frame, a head rotatably

mounted on said slide and carrying a tool arm, a tubular member slidably mounted on said arm, a spindle rotatably mounted in said tubular member and carrying a tool at its outer end, and means for moving said tubular member endwise of said arm.

34. In apparatus of the class described, the combination of a support, a pair of connected members rotatably mounted on said support, means for oscillating one of said members, a pair of radially movable elements, one carried by one of said members and the other carried by said support, a disk, a pair of dogs carried by said elements respectively and arranged to alternately lock the disk to one of said elements, means for operating said elements, and means for adjusting one of said dogs in a direction substantially circumferentially of the disk.

35. In apparatus of the class described, the combination of a support, a pair of connected members rotatably mounted on said support, means for oscillating one of said members, a pair of radially movable elements, one carried by one of said members and the other carried by said support, a disk, a pair of dogs carried by said elements respectively and arranged to alternately lock the disk to one of said elements, means for operating said elements, and means for adjusting the dog carried by the element mounted on said support in a direction substantially circumferentially of the disk.

36. In apparatus of the class described, the combination of a support, a pair of connected members rotatably mounted on said support, means for oscillating one of said members, a pair of radially movable elements one carried by one of said members and the other carried by said support, a disk having a flanged circumferential edge formed with a plurality of spaced notches, a pair of dogs carried by said elements respectively and disposed above and below the flange of the disk alternately engaging the notches therein to lock the disk to one of said elements and means for operating said elements.

37. In apparatus of the class described, the combination of a support, a pair of members rotatably mounted on said support, means for oscillating one of said members, a pair of radially movable elements, one carried by the member which is oscillated, and the other carried by said support, a disk connected to the other member, dogs carried by said elements and alternately engaging said disk, devices on said elements correlated to connect said elements together during a portion of the movement of the oscillated member, and means carried by said oscillated member and engaging the element movably mounted thereon for operating it, and a trip device on said support for operating said operating means.

38. In apparatus of the class described, the

- combination of a support, a pair of members rotatably mounted on said support, means for oscillating one of said members, a pair of radially movable elements, one carried by the member which is oscillated, and the other carried by said support, a disk connected to the other member, dogs carried by said elements and alternately engaging said disk, devices on said elements correlated to connect said elements together during a portion of the movement of the oscillated member, means carried by said oscillated member and engaging the element movably mounted thereon for operating it, and a trip device on said support for operating said operating means, and means for preventing the movement of said operating means throughout a portion of the movement of said oscillated member.
39. In apparatus of the class described, the combination of a support, a pair of members rotatably mounted on said support, means for oscillating one of said members, a pair of radially movable elements, one carried by the member which is oscillated, and the other carried by said support, a disk connected to the other member, dogs carried by said elements and alternately engaging said disk, devices on said elements correlated to connect said elements together during a portion of the movement of the oscillated member, and means carried by said oscillated member and engaging the element movably mounted thereon for operating it, and a trip device on said support for operating said operating means, and means for adjusting said trip device.
40. In apparatus of the class described, the combination of a frame, a carriage mounted to reciprocate thereon, a pair of members rotatably mounted on said carriage in concentric relationship, a pair of casing members one of which is connected to said carriage, and an indexing mechanism within said casing members, said mechanism including elements serving to periodically connect and disconnect said members, and a trip device carried by the other casing member.
41. In apparatus of the class described, the combination of a frame, a carriage mounted to reciprocate thereon, a pair of members rotatably mounted on said carriage, a casing connected to said carriage, and an indexing mechanism within said casing, said mechanism including elements serving to periodically disconnect and connect said members.
42. In apparatus of the class described, the combination of a frame, a carriage mounted to reciprocate thereon, a pair of members rotatably mounted on said carriage in concentric relationship, a pair of casing members one of which is connected to said carriage, an indexing mechanism within said casing members, said mechanism including elements serving to periodically connect and disconnect said members and a trip device carried by the other casing member, and means for adjusting said trip device.
43. In apparatus of the class described, the combination of a frame, a carriage mounted to reciprocate thereon, a pair of detachably connected members rotatably mounted on said carriage, means for rotating said members, means for reversing the direction of rotation of said members, means connecting one of said members to the frame and adapted to translate the rotation of said member into rectilinear movements of said carriage, a planular faced tool, means for maintaining said planular face on the tool and means for adjusting said tool endwise of its axis relative to one of said rotatable members.
44. In apparatus of the class described, the combination of a frame, a carriage mounted to reciprocate thereon, a pair of detachably connected members rotatably mounted on said carriage, means for rotating said members in one direction and then in the reverse direction, connections between one of said members and the frame adapted to translate the rotational movement of the member connected to the frame into reciprocatory movements of said carriage, a tool, and means for adjusting the tool endwise of its axis relative to one of said members.
45. In apparatus of the class described, the combination of a frame, a carriage mounted to reciprocate thereon, a rotatable member mounted on the carriage, means for reversibly rotating the rotatable member, connections between said member and the frame adapted to translate the rotational movement of the member into reciprocatory movements of the carriage, a tool, a tool spindle, and means for adjusting the tool endwise of its axis relative to the axis of rotation of the rotatable member.
46. In apparatus of the class described, the combination of a frame, a carriage mounted to slide on said frame, a pair of relatively movable members, indexing means for detachably connecting said members together, a work piece carried by one of said members, power means connected to the other member and operating through said indexing means to oscillate the work carrying member, a segment connected at one end to the member to which said power means are connected, a device rotatably fitting the work carrying member for supporting the other end of said segment, and flexible members connected to said frame and arranged to wind on and from said segment.
47. In apparatus of the class described, the combination of a frame, a carriage mounted to slide on said frame, a pair of relatively movable members, indexing means for detachably connecting said members together, and means for adjusting said indexing means.

a work piece carried by one of said members, power means connected to the other member and operating through said indexing means to oscillate said work carrying member, a segment connected at one end to the member to which said power means are connected, a device rotatably fitting the work carrying member for supporting the other end of said segment, flexible members connected to said frame and arranged to wind on and from said segment, and means for detachably connecting the ends of said segment to said member and said device.

48. In apparatus of the class described, the combination with a frame, of a slide mounted thereon, a work carrying spindle on the slide, a planular faced tool, a casing therefor, a tool spindle, means for operating said work carrying spindle and slide to impart to the work carried by said spindle a generating motion relative to said tool, means for moving said tool spindle endwise to adjust the tool relative to the work, and means cooperating with the casing for maintaining the position of the grinding plane of the tool relative to the casing.

49. In apparatus of the class described, the combination of a frame, a carriage mounted thereon, a work carrying spindle on said carriage, a planular faced tool, a spindle for said tool, means for operating said work carrying spindle and carriage, operable means for moving the tool spindle endwise to adjust the tool relative to the work, moving means disconnectibly connected with said operable means and adjustable relative thereto when disconnected, an element associated with the tool spindle adapted to be moved by said moving means, a stop carried by said frame, and a stop associated with said operable means and operatively engaging the stop carried by the frame whereby the planular face of the tool is positioned in a predetermined plane on the machine, and whereby, when the said moving and operable means are adjusted relative to each other by a predetermined amount, the tool face is shifted out of said plane by a corresponding amount.

50. In apparatus of the class described, the combination of a frame, a carriage mount-

ed thereon, a work carrying spindle on said carriage, a planular faced tool, a spindle for said tool, means for operating said work carrying spindle and carriage, operable means for moving the tool spindle endwise to adjust the tool relative to the work, moving means disconnectibly connected with said operable means and adjustable relative thereto when disconnected, a first screw threaded element connected with the tool spindle, a second screw threaded element meshed with the first screw threaded element, connections between said moving means and the second screw threaded element for turning the latter to thereby propel the first screw threaded element, a stop carried by said frame, and a stop associated with said operable means and operatively engaging the stop carried by the frame whereby the planular face of the tool is positioned in a predetermined plane on the machine, and whereby, when the said moving and operable means are adjusted relative to each other by a predetermined amount, the tool face is shifted out of said plane by a corresponding amount.

51. In a grinding apparatus, a frame, a work support on the frame, a grinding wheel spindle on the frame, a grinding wheel on the wheel spindle, operable means for moving the wheel spindle to adjust the position of the wheel relative to the work support, moving means disconnectibly connected with said operable means and adjustable relative thereto when disconnected, an element associated with the wheel spindle adapted to be moved by said moving means, a stop carried by said frame, and a stop associated with said operable means and operatively engaging the stop carried by the frame whereby the working surface of the wheel is positioned in a predetermined working zone on the machine, and whereby, when the said moving and operable means are adjusted relative to each other by a predetermined amount, the working surface of the wheel is shifted out of said zone by a corresponding amount.

In testimony whereof, I have hereunto signed my name.

CHARLES H. SCHURR.
